(57) **CLAIM**

I claim the ornamental design for a sign, as shown and described.

DESCRIPTION

FIG. 1 is a front perspective view of a sign of the present invention.

FIG. 2 is a rear perspective view of FIG. 1.

FIG. 3 is a front view of FIG. 1.

FIG. 4 is a left side view of FIG. 1, the right side being a mirror image to the left side.

FIG. 5 is a top view of FIG. 1.

FIG. 6 is a bottom view of FIG. 1; and,

FIG. 7 is a rear view of FIG. 1.

In the drawings, the broken lines illustrate environment and form no part of the claimed design.
